UNITED STATES PATENT OFFICE.

JOHN SELLERS BANCROFT, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

KEYBOARD MECHANISM FOR PERFORATING-MACHINES.

No. 871,080.

Specification of Letters Patent.

Patented Nov. 12, 1907.

Application filed October 29, 1903, Serial No. 179,048. Renewed May 29, 1905. Serial No. 262,902.

To all whom it may concern:

Be it known that I, JOHN SELLERS BANCROFT, of Philadelphia, in the county of Philadelphia, State of Pennsylvania, have invented certain new and useful 5 Improvements in Keyboard Mechanisms for Perforating-Machines; and I do hereby declare the following to be a full, clear, and exact description of the same, reference being had to the accompanying drawings, forming a part of this specification, and to the figures 10 and letters of reference marked thereon.

This invention relates to a key board mechanism especially designed for use in connection with record-strip perforating machines, but alike applicable to other varieties of keyboard machines.

15 Keyboard perforators, as heretofore generally constructed, possess structural limitations tending to obstruct rather than facilitate the most convenient or desirable arrangement of the characters represented by the keys. This is due, in a measure, to the circumstance that the space-value of each type, as transmitted 20 to the line measuring or recording mechanism, is determined by a single punch or combination of punches common to all types of the same space-value, hence the actuating or transmitting devices are arranged in sets 25 or groups each controlled by keys representing a common space-value. As a result, the keys representing the same space-value are grouped together, and, while interchangeable, as to position, among themselves, they cannot be separated from their own group and 30 located among the keys of another group whose space value is different.

One object of the present invention is to partially or wholly eliminate this restriction and enable the characters to be distributed and arranged according to 35 any desired system, irrespective of their individual space-value, to which end the invention consists in the employment of a system of permutation members or translating devices, whereby the motion of any key may be transmitted to any one or more of the punches 40 and admeasuring devices of the line register, as hereinafter described.

Another object of the invention is to materially diminish the number of valves employed in connection with machines of the monotype class for designating 45 or bringing into action such of the punches as are appropriated to individual keys, and this is accomplished by providing each punch with a control valve, and coupling the latter with the keys in such manner that each key will actuate the valve or valves representing 50 the punch or punches corresponding therewith, whereby not only is the mechanism greatly simplified but the loss of pressure incident to leakage is diminished. The invention also includes minor features relating to the construction and arrangements of parts,

all as hereinafter fully described and pointed out in 55 the claims.

In the accompanying drawings illustrating a preferred form of embodiment:—Figure 1 is an end elevation of a keybank with permutation members arranged for operating the punch controlling valves of a record 60 strip punching machine. Fig. 2 is a front elevation of one of the punch-cylinder blocks. Fig. 3 is a partial top plan view of the permutation system and connections, with the keybank removed. Fig. 4 is a diagrammatic view of the connections. Fig. 5 is a 65 perspective view of a portion of the permutation system. Figs. 6 and 7 illustrate modifications of the permutation system. Fig. 8 is a perspective view of one form of valve actuating bar. Fig. 9 is a plan view of the modified construction Fig. 6 illustrating the equipment 70 for a single column of keys, but one key being shown in position to avoid obscuring underlying parts. Fig. 10 is a similar view with the valve actuating bar of Fig. 8 applied as a substitute for the valve cross bar of Figs. 6 and 9. Fig. 11 is a plan view of the modified 75 construction Fig. 7 showing the equipment for a column with a single key of the series in position. Fig. 12 is a similar view embodying the modified valve actuating bar of Figs. 8 and 10.

Like numerals designate corresponding parts in the 80 several figures.

With the exception of the actuating and control mechanism intermediate the keys and the punching, measuring and indicating mechanisms, the machine illustrated is substantially that of Patent No. 654,115, 85 with the improvements of Patent No. 828,449 of August 14, 1906 applied thereto. It includes among its distinguishing features, a paper feed mechanism, a punching mechanism, a line measuring mechanism, a justification scale mechanism, a space type indicating mechanism and a resetting mechanism, all controlled by the keys of a keybank. 90

In the commercial machine there are two hundred and twenty five keys, thirty one punches and thirty two punch-bars, fourteen of the latter representing 95 progressive degrees of adjustment, another fourteen representing corresponding adjustments in a transverse direction to the first, and, in addition, designating degrees of adjustment of the mold, while of the remaining four one is blank, one represents the justifying space type, and two the justification designating signals. Of the last named four, two operate upon the measuring devices, making sixteen in all, and for purposes of description this group or series of sixteen punch-bars is designated the space-value group in that they 100 all operate upon and affect the movements of the line measuring mechanism.

In the prior machine each punch bar was provided

- with a motor, the latter, with one exception, *i. e.*, the justification space punch-bar, being controlled, through valves, by all the keys in a column or line, accordingly as it belonged to the space-value or non space-value group, hence each key was equipped with a valve for this purpose, there being not less than two hundred and twenty five valves employed. According to this arrangement the keys of each row or column controlled but a single space-value punch-bar or punch, hence the area available for the distribution of characters on the keyboard was circumscribed, and, because of the multiplicity of valves, the waste of pressure, due to leakage, as well as the cost of construction, adjustment and maintenance was excessive.
- 15 Inasmuch as the present improvements have to do with the control elements rather than with the composition of the several mechanisms controlled, it is deemed sufficient for present purposes to designate the latter by their actuating members, such as the punch-bars 1 and the rocking frame 2, through which the motors act upon the punching and measuring mechanisms. Thus each punch-bar carries a projection or shoulder 3 for engaging the rocking frame 2, and, in addition, each bar of the space-value group is coupled to one of the series of stop-bars 4, of the line measuring mechanism. The paper feed is acted upon by the rocking frame 2, and the escapement of the line measuring mechanism, by the space-value group of punch bars acting alone or in conjunction with said rocking frame.
- 20 The punch-bar motors are arranged in two series on opposite sides of the punch-bars and each comprises a cylinder 5 formed in a block 6 and containing a piston 7 engaging one arm of a bell-crank lever 8, the latter supported in bearings 9 on block 6 and having its other arm engaging a pin 10 on the punch-bar. The rear ends of the cylinders are closed by a plate 11 containing a port 12 for each cylinder and each port is connected by a pipe with a separate control valve 13. These valves 13 (one for each motor and punch-bar, thirty two in all) are entirely independent of the keys and are preferably located in a common valve chamber 14 communicating, as through pipe 15, with the pressure supply, and each valve co-operates with two ports, the one 16, connected to the port 12 of one of the motor cylinders, and the other, 17, opening to the atmosphere. When in normal or inactive position each valve covers ports 16 and 17 placing them in communication and thus opening the exhaust for the motor; and when advanced to active position the valve uncovers port 16 thereby admitting pressure to the motor and causing the operation of its punch-bar.
- 25 It is the office of the finger keys to select and actuate such of the valves 13 as represent the characters or functions designated by the key operated; and in order that this may be done without regard to the special location of the key the following permutation system for controlling the valves has been devised, whereby any key of the series may be utilized for operating any one or more of the punch-bars and register the space value of the type designated thereby, thus not only permitting any desired arrangement of the characters on the keybank but removing the limitations heretofore imposed upon the dimensioning of the key bank, due to column control of the measuring mechanism. Coupled with the stem of each valve 13 is an

actuator preferably in the form of a bar 18 guided to reciprocate longitudinally in supports 19. The several actuators 18, one for each valve, are disposed in parallel relation to one another and to a second set or series of similar bars 20, denominated permutation bars, equal in number to the keys of the keybank.

The keys, preferably arranged in series in parallel columns, are in the form of bell-crank levers 21, one arm furnished with a designating finger piece or button 22 and the other with a cross-head 23, the latter preferably bridging or extending over a series of the permutation bars (Fig. 3) in order that the same form of key lever may be used throughout the column to engage any one of the permutation bars pertaining thereto. Each permutation bar 20 is furnished with a shoulder 24 or arm 24 in front of one of the cross-heads 23, there being at least one permutation bar for each key lever. The permutation bars are also each provided with one or more, usually two, designating or selecting arms or bearings 25, 26, located and arranged in opposite relation to corresponding arms or bearings 27, 28 on the valve actuating bars 18.

Between the opposing bearings 25, 26 and 27, 28, and extending across the two series of bars 18, 20, are arranged a plurality of interponents 29, 30 for transmitting motion from one series of bearings to the other. In the present instance the interponents are represented by the bars 29, 30, each supported on arms 31, carried by a rock shaft 32, and to render the mechanism as a whole more compact the bearings as well as the interponents are divided into two groups or series and arranged in different planes, one group representing the space-value punch bars and their valves and the other the non-space value punch-bars. Thus the interponents 29 carried by the longer arms 31 together with bearings 25 and 27 co-operating therewith may represent the space-value group of valves, and the interponents 30 on the shorter arms together with the bearings 26 and 28 may represent the non space value punch bars, or vice versa. This separation and designation of function as between the control mechanism for the two series of valves is of further advantage in assembling the mechanism, as it enables the operator to distinguish at a glance by the location and length of the respective projections or bearings both the series and the number of each series which any given permutation bar will control.

The permutation, interponent and actuator bars are preferably disposed at an angle to the horizontal so that they will be returned by gravity, being assisted in this by the pressure upon the valve stems; but this may be supplemented, if desired, by the addition of springs, weights or equivalent means.

The action and capacity of the permutation system as applied to the controlling valves of the perforating and measuring mechanism will readily be understood by reference to the diagrammatic view, Fig. 4. Bearing in mind that each permutation bar 20 represents a key and each actuator bar 18 a valve, and that each interponent 29, 30, controls any or all of the actuator bars 18, and is in turn subject to the control of any or all the interponents, it is obvious that by a proper disposition of its engaging bearings 25, 26, any key, acting through its permutation bar, may be made to actuate any one or more of the series of valves and thus produce

the designating signals or perforations on the record strip and admeasure the space-value of the type represented by or assigned to said key. Thus by the use of thirty two control valves in place of the two hundred and twenty five valves heretofore employed all the combinations necessary for the production of the various signals can readily be produced.

Instead of operating the valves of the space-value and non-space value groups of punch-bars through separate sets of actuating bars, interponents and selecting bearings, the valves pertaining to one group of punch-bars may be so operated and those of the other group actuated more directly from the keys, by causing a series of permutation bars pertaining to a column of keys, or 15 the keys of a column, to engage an interponent common to such series and acting upon one of the valves. Thus in the modification illustrated in Figs. 6 and 9 wherein the valves pertaining to the two groups of punch bars are shown located in different planes, each valve 13 20 of one group is provided with an interponent in the form of a cross-bar 33 arranged intermediate the valve stem and the ends of the permutation bars, said cross-head extending across and being engaged by a plurality of permutation bars. In this case the number 25 of valves would be the same, but the flexibility of the system would be diminished by reason of the fact that a plurality of permutation bars instead of each permutation bar would control each valve of one group. If the number of permutation bars acting upon a given 30 valve coincides with the number of keys in a column the same result could be attained by providing each valve with an actuator bar 34, Fig. 8, provided with arms or bearings 35 equal in number to the keys in a column, said bars being located at intervals among the 35 permutation bars in such relation to the keys of the several columns that all of the keys in any one column will be caused to operate through its bar 34 to shift valve 13 of one group, while the same key will operate through the permutation bar to shift a valve of the 40 other group as illustrated in Fig. 10.

The modification, Figs. 7, 11 and 12 is similar to that of Figs. 6, 9 and 10 with this exception, that the group of valves controlled through the selecting shoulders or bearings of the permutation bars are coupled with the 45 shafts of the interponent bars, the supporting arms or connections serving as the actuators for transmitting motion from the interponents to their respective valves.

Having thus described my invention, what I claim as new and desire to secure by Letters Patent, is:—

50 1. In a perforating mechanism such as described the combination of the following elements to wit:—two series of punch bars in parallel relation; a plurality of pistons and cylinders, one for each punch bar, disposed in planes transverse to and intersecting the punch-bars; and a 55 series of bell-cranks, one for each punch bar, coupled with said pistons.

2. In a perforating machine such as described, the combination with the series of punch bars, of actuating devices therefor comprising two groups of pistons and cylinders disposed on opposite sides of the punch bars and at an angle thereto, and a bell crank-lever intermediate each piston and its punch bar.

60 3. In a perforating machine such as described, the combination with the punch bars of actuating devices therefor comprising a group of cylinders formed in a block, a plate closing the rear ends of said cylinders, bearings supported upon the block, pistons, and bell crank levers mounted in said bearings and each engaging a pin or shoulder on one

of the punch bars, and being engaged by one of said pistons. 70

4. In a perforating machine such as described, the combination with the series of punch bars and the individual motors therefor, of the series of control valves, one for each motor, a key bank, and an actuating mechanism intermediate said key-bank and the series of valves, provided 75 with a series of permutation devices.

5. In a perforating machine such as described provided with a series of punch bars, a series of individual motors and a valve for each motor, and in combination therewith a keybank provided with a series of keys, and an actuating mechanism or system intermediate the keys and valves comprising a series of permutation bars, one for each key, a series of valve actuating bars, one for each valve, and a series of interponents, the latter arranged intermediate 80 the valve actuating and permutation bars and between oppositely located shoulders thereon. 85

6. In a perforating machine such as described the combination of the following elements, to wit: a series of punch-bars; a motor and valve for each punch bar; control means for the measuring mechanism acted upon by 90 the punch bars; a series of actuators, one for each valve; a series of keys; a series of permutation bars; and a series of interponents intermediate the permutation bars and the valve actuators. 95

7. In a perforating machine such as described the combination of the following elements, to wit; a plurality of punch bars; a control member for the measuring mechanism operatively connected with the punch bars; a motor device for the punch bars provided with individual control means; a plurality of actuating devices or bars for said 100 control means; a plurality of permutation bars each provided with selecting shoulders or arms; and a plurality of interponent bars intermediate the actuating devices for the punch-bar control means and said permutation bars. 105

8. In a perforating machine such as described the combination of the following elements, to wit; a plurality of punch-bars divided into two groups; a control member for the measuring devices and paper feed, operatively connected to one of said groups of punch-bars; a motor for each punch-bar provided with a control valve; a plurality 110 of actuators, one for each valve; a series of keys; a plurality of permutation bars, one for each key provided with selecting shoulders, and a plurality of interponents intermediate said permutation bars and valve actuators.

9. In a keyboard mechanism for perforating machines 115 such as described the combination of the following elements to wit; a plurality of control valves; an inclined series of actuator bars; a transverse series of pivoted interponent bars; a plurality of inclined permutation bars; and a series of finger keys, each connected to one of the 120 permutation bars.

10. In a keyboard mechanism for perforating machines such as described provided with a series of punch-bars divided into two groups the one representing position and the other position and space-value, and a controlled device 125 for the measuring mechanism coupled with the group of space-value punch bars and in combination therewith the following elements, to wit; a plurality of motors, one for each punch bar; a valve for each motor provided with an actuator bar; a series of permutation bars; a series of interponents, each engaging one of the valve actuator bars; and a plurality of selecting shoulders applied to each permutation bar in position to engage an interponent coupled with the positioning punch bar group and another coupled with the positioning and space value group of punch bars. 130 135

11. In a keyboard mechanism for perforating machines such as described, the combination of the following elements, to wit; a series of parallel longitudinally movable actuator bars each furnished with an engaging shoulder, and comprising a plurality of groups distinguished by the 140 difference in the height or projection of their engaging shoulders; a series of longitudinally movable permutation bars parallel with the actuator bars and provided with selecting shoulders of different height or degree of projection; and two series of laterally movable interponent bars located between and extending laterally of the permutation and actuator bars and in different planes. 145

12. In a keyboard mechanism for perforating machines

- such as described the combination of the following elements, to wit; a series of parallel longitudinally reciprocating actuator bars provided with engaging shoulders in two planes; a series of longitudinally reciprocating permutation bars parallel with the actuator bars and provided with selecting shoulders in two planes; and two series of interponent bars extending in different planes transversely of and intermediate the permutation and actuator bars.
- 10 13. In a perforating machine such as described, the combination of the following elements, to wit; a series of punch-bars; controlling devices for the line measuring mechanism coupled with a group of said punch-bars; a motor for each punch-bar; a series of control valves, one for each motor; a keybank; and actuating devices for transmitting motion from each key to two control valves of which one pertains to the group of punch bars coupled with the measuring mechanism.
14. In a perforating machine such as described the combination of the following elements, to wit; a series of punch bars; controlling devices for a line measuring mechanism coupled to a group of said punch-bars; a series of motors, one for each punch-bar; a valve for each motor; a keybank; and connections intermediate the keys and said series of valves for simultaneously actuating a plurality of said valves including one of the series connected with the group of punch-bars coupled with the measuring mechanism.
15. In a perforating machine provided with a plurality of punches each coupled with a motor and in combination therewith, a plurality of valves, one for each motor, an actuating device for each valve and a series of keys controlling each actuating device.
16. A pneumatic keyboard, comprising a series of de-
35 pressible keys, a series of subjacent and parallel actuating bars operated upon by the keys, a valve chamber or air trunk arranged outside the bank of keys, and valves in the valve chamber or air trunk connected to and operated by said bars.
- 40 17. A pneumatic keyboard comprising a bank of keys and a marginal air trunk or valve chamber outside the range of the bank of keys, two series of valves in the air trunk or valve chamber and means for simultaneously operating one valve of each series by each of the keys.
- 45 18. A pneumatic keyboard, comprising a series of de-
pressible keys, a series of subjacent parallel actuating bars operated upon by the keys, an air trunk arranged outside the bank of keys and having a plurality of outlets and valves connected to the actuating bars and controlling said outlets.
19. A pneumatic keyboard, comprising a series of de-
50 pressible keys, a series of subjacent parallel actuating bars operated upon by the keys, an air trunk or valve chamber arranged outside the bank of keys, valves arranged in the air trunk or valve chamber and operated by the actuating bars, and means for returning said actuating bars.
20. A pneumatic keyboard, comprising a series of de-
55 pressible keys, a series of subjacent parallel actuating bars operated upon by the keys, an air trunk or valve chamber arranged along the margin of and outside the bank of keys, 60 valves arranged in the air trunk or valve chamber and a detachable cover for the trunk or chamber.
21. In a pneumatic keyboard, the combination of a key-
65 bank, an air-pressure chamber contiguous thereto, a series of valves independent of the keys and each controlling an outlet from said air-pressure chamber, and means for simultaneously and selectively operating a plurality of said valves by the depression of a single key.
22. In a key actuated mechanism, the combination of two series of actuating bars and means for selectively 70 operating any bar of one series simultaneously with any bar of the other series, said bars being adapted to actuate movable parts contiguous thereto.
23. In a pneumatic keyboard, the combination of a valve, 75 a plurality of keys, and means connecting said valve with said keys, whereby the valve may be operated by any of said keys.
24. In a pneumatic keyboard the combination of a se-
80 ries of control valves, a plurality of keys, and means connecting said valves and keys so that any one or more of the valves may be operated by any key.
25. In a pneumatic keyboard provided with a plurality 85 of punches each coupled with a separate control valve and in combination therewith a plurality of keys and means for coupling two or more of said valves with individual keys.
